(57) **CLAIM**

The ornamental design for belt-worn control unit for LED headlight, as shown and described.

DESCRIPTION

FIG. 1 is a front, top, side perspective view of a belt-worn control unit for LED headlight, showing my new design;

FIG. 2 is a front view thereof;

FIG. 3 is a top view thereof;

FIG. 4 is a bottom view thereof;

FIG. 5 is a back view thereof; and,

FIG. 6 is a side view thereof.

The broken line portions of the figure drawings are included to show unclaimed subject matter only and form no part of the claimed design.
